UNITED STATES PATENT OFFICE.

IWAN BOJKO, OF ROME, NEW YORK.

COMBINED BRUSH AND COMB.

1,259,570.

Specification of Letters Patent. Patented Nov. 23, 1920.

Application filed June 16, 1920. Serial No. 389,515.

To all whom it may concern:

Be it known that I, IWAN BOJKO, a citizen of Ukraine, residing at Rome, county of Oneida, and State of New York, have invented certain new and useful Improvements in Combined Brushes and Combs, of which the following is a specification.

This invention relates to improvements in toilet articles, particularly to improvements in combs, and it is the principal object of the invention to provide a combined hair brush and comb, in which the comb is adapted to be placed within a recess formed within the brush in a ready and convenient manner.

A further object of the invention is to provide a combined comb and brush in which the comb is easily brought into its operating position and held therein.

These and other objects which will become apparent as the description proceeds, are attained by the novel construction, arrangement of elements and combination of parts hereinafter more fully described and shown in the accompanying drawing, forming a material part of this application and in which—

Figure 1 is a top plan view of the combined comb and brush constructed according to the present invention with the comb in its operating position.

Fig. 2 is a side view thereof, and

Fig. 3 is an end view.

The bristles 10 of the brush 11 are engaged in the usual manner within a backing 12 in which is formed a recess 13, and a handle 14 is made integrally with this backing. The comb has the customary plurality

of teeth 15 and its back is provided near the ends of the same with suitable perforations 40 in alignment with similar perforations in the brush-backing so that pins 16 provided with heads 17 may be passed through the perforations of the brush-backing and the comb back with their heads 17 resting on 45 top of the brush-backing 12, if it is desired to hold the comb to the brush in its operating position shown in Fig. 1.

If it is desired, as for instance when packing a suit case for traveling, to place 50 the comb into the recess 13 of the brush-backing, the pins 16 are removed and the comb is turned to enter with its teeth first the recess 13, whereafter, the pins are again placed into the perforations in the brush-back and comb in an obvious manner to hold the comb within the brush-back recess.

It will be understood that changes may be made in the minor details of the device without departing from the spirit and scope 60 of my invention, but what I claim is—

A combined brush and comb comprising a perforated brush-backing, provided with a longitudinal recess, a handle formed with said backing, a comb having a perforated 65 back, the perforations of said brush-backing and said comb back adapted to be brought into alignment, and headed pins adapted to be passed through said perforations to hold the comb in its operating position at the 70 edge of said brush-backing and to secure said comb in reversed position within the recess of said brush-backing.

In testimony whereof I have affixed my signature.

IWAN BOJKO.
